UNITED STATES PATENT OFFICE.

GEORGE L. BOTTUM, OF CHICAGO, ILLINOIS.

THERMOSTATIC VALVE.

1,147,297.

Specification of Letters Patent. Patented July 20, 1915.

Application filed June 15, 1914. Serial No. 845,063.

To all whom it may concern:

Be it known that I, GEORGE L. BOTTUM, a citizen of the United States, residing at Chicago, in the county of Cook and State of Illinois, have invented new and useful Improvements in Thermostatic Valves, of which the following is a specification, reference being had to the accompanying drawings, forming a part thereof.

10 The purpose of this invention is to provide an improved valve construction for a hot-water system, having means for automatically closing at a predetermined temperature determined by the adjustment of 15 the valve.

It consists in the elements and features of construction shown and described as indicated in the claims.

In the drawings: Figure 1 is a side elevation of a valve embodying this invention. Fig. 2 is an axial section of the same at the line 2—2, on Fig. 1. Fig. 3 is a section at the line 3—3 on Fig. 2. Fig. 4 is a detail section of a thermostatic or heat-responsive member.

The valve shown in the drawings comprises a casing consisting of a body member, 1, having the inlet, 2, and outlet, 3, the inlet, 2, being adapted to be closed by a piston valve, 4, which is preferably in the form of a disk, 4^a, having guide wings, 4^b, so that the valve may be wide open,—that is, may have its disk or head, 4^a, which closes the port withdrawn therefrom a distance sufficient to admit between it and the entrance to the valve port fluid to the amount of the full capacity of said port while still guided perfectly by the port walls. The piston valve, 4, is carried by a two-part stem comprising 20 parts, 5 and 6, which are parted and lapped upon each other for relative longitudinal movement at a diametric plane, extending from the shoulder, 5^a, of the member, 5, to a shoulder, 6^a, of the member, 6, the 25 end of the member, 6 abutting upon the shoulder, 5^a, and the end of the member, 5, abutting upon the shoulder, 6^a, when the two members are fully lapped, as shown in Fig. 2. The member, 6, is connected 30 with the valve, 4, by the expansible heat-responsive member, 8, hereinafter more particularly described; and the member, 5, of the stem protrudes from the casing and is provided with an operating handle, 9. The 35 casing comprises, beside the body member, 1, a closure and stem-bearing member, 10,

which is screwed into the upper end of the body, 1, closing an opening in said body large enough to admit the expansive heat-responsive member, 8, which is considerably 40 greater in diameter than the piston valve to which it is directly connected at the lower end. Upon the stem member, 6, there is cut a square-form quadruple thread, as shown at 6^t, which engages the corresponding 45 female thread in the central aperture of the closure member, 10, of the body, and is of sufficient pitch to give the valve, 4, its full movement from fully closed to fully open position by somewhat less than one full turn 50 of the stem. The stem member, 5, has near its upper end within the casing an annular boss, 5^b, having a tapering shoulder facing outward and an abrupt shoulder facing inward. The closure member, 10, of the body 55 is axially apertured from end to end and has at its upper end a bushing, 11, apertured for the upper end portion of the stem member, 5, which is reduced at the upper end to pass through said aperture of the bushing which is screwed into the upper end of 60 the said closure member, 10. The bushing is counterbored at the inner end around the stem aperture, and in said counterbore there is lodged a sleeve, 12, preferably of indurated fiber, whose inner end is conically bored to form a seat for the outer tapering shoulder of the boss, 5^b, on the stem member, 5. The inner abrupt shoulder of said boss receives the thrust of a coil spring, 15, a wearing 65 washer, 16, being interposed between the end of the spring and said shoulder, the lower end of said spring being stopped upon an abrupt shoulder, 10^a, on the casing closure member, 10. The said closure member may 70 be chambered out at the lower part, as shown at 10^c, above a sufficient threaded portion for engagement of the threaded stem as described to within a sufficient distance of the shoulder, 10^a, to leave sufficient material below 75 said shoulder, which results in an inwardly-protruding annular boss, 10^c, the upper side of which is the shoulder, 10^a, which boss forms a guide seat for the stem at the portion where it consists of the lapped and 80 sliding end portions of the two members, 5 and 6. The spring, 15, interposed, as described, between the upwardly facing shoulder, 10^a, of the casing closure member and the downwardly-facing abrupt shoulder 85 of the stem member, 5, serves to seat the tapering shoulder, 5^b, of the stem in the 90

conical seat provided for it in the lower end of the indurated fiber sleeve, 12, and dispenses with the necessity for any packing around the stem at its emergence from the 5 casing. On the annular tablet, 10°, which results from the relatively large diameter of the closure member, 10, at the lower end where it is screwed into the body member, 1, and the lesser diameter of the upper portion 10 of said closure member which houses and guides the stem, there is inscribed a scale graduated in degrees of temperature from a relatively low temperature at which the valve is designed to be set wide open to 15 a higher temperature, at which it is designed to be closed; as, for example, from 110 degrees F. to 250 degrees F., as shown in Fig. 3.

The operating handle, 9, of the valve stem 20 carries an index finger, 17, which extends down alongside the reduced upper portion of the closure member so as to traverse the graduated scale as the stem is rotated through the one revolution which is sufficient 25 to move the valve from wide open to fully closed position. It will be observed that in such rotation of the stem, the upper member, 5, will not have any longitudinal movement, but the lower member, 6, partaking 30 fully of the rotative movement by reason of the engaging lap of the flat diametric faces of the two members upon each other will receive also the longitudinal movement due to the threaded engagement of said 35 lower member with the body, the two members, 5 and 6, sliding upon each other in the longitudinal movement which the member, 6, thus receives for opening and closing the valve. For more perfectly insuring the concentricity of the two members, 5 and 6, they 40 may each be axially bored, the bore constituting semi-cylindrical channels in their flat diametric faces, and a guide pin, 18, screwed into one of said members, preferably 45 the upper member, and entering the bore of the other member, which fits accurately, will insure the two members remaining concentric at their lapped portions. The 50 precaution involved in providing this guide pin is not usually necessary, because the stem members are seated at their lapped portion, as stated, in the annular boss, 10°.

The expansible or heat-responsive member, 8, will now be described. It consists of 55 a plurality—as illustrated, four,—of flat chambers, 8^a, both walls of which are corrugated to adapt them to the necessary change of form involved in expanding the chambers without contracting their diameter. 60 Each of the chambers, 8^a, is formed of two members, each of which is in general cup-shaped, the wall of the cup in each case being V-shaped in radial section, and the bottom or disk member of the cup being corrugated. The two cup-shaped members are

connected by lodging the V-shaped wall of one in the V-shaped wall of the other, one member being enough larger than the other to permit them to be thus engaged, the engagement being effected by springing outward the corrugated bottom of the member whose V-shaped wall is to be engaged within the V-shaped wall of the other. The V-shaped walls thus seated, one within the other, are first solder-coated so that they may be sweated together, and the reentrant angle of the V-shaped wall of the outer-seated member is then filled with solder, 20, as shown, so not only producing a perfectly secure and non-leaking joint, but also making each of said chambers peripherally rigid, which necessitates the expansion which may take place being accommodated by the flexibility of the corrugated walls. At the center, both diaphragms forming 75 the chamber are apertured, and the adjacent diaphragms of adjacent chambers are secured together by hollow rivets, 21, each clenched down upon a washer, 22, as seen clearly in Fig. 4. It will be understood that 80 these adjacent walls of adjacent chambers are riveted together before the other wall of each chamber is coupled to it by the engagement of the V-shaped peripheries secured by solder, as described.

The outer wall of one of the outermost chambers, 8, has its central aperture closed by a solid rivet, 23, and the outer wall of the other outermost chamber has its central aperture closed by a hollow rivet, 24, the 100 solid rivet having a threaded tang for screwing into the stem member, 6, and the hollow rivet having a similarly threaded stem for screwing into the head of the valve, 4. Before connecting the expansible member with the stem and valve, the chambers of all the members, 8^a, are filled with some suitable expansible liquid, as wood alcohol, which is poured in through the hollow rivet, 24, the rivet itself being filled to the top, and the 110 valve, 4, is then screwed on to said hollow rivet, closing it perfectly; and if desired, the surfaces having been first solder-coated, the rivet may be soldered to the head of the valve by applying sufficient heat to 115 cause the solder to flow and set. Usually, however, it will be sufficient to screw the rivet home tightly to the valve, the joint being made tight in any method familiar for making threaded joints tight.

In operation, as indicated, the valve will be wide open when the chambers, 8^a, are not expanded, and the valve, 4, is withdrawn to its highest position, at which highest position the pointer, 17, will stand at the highest point on the graduated scale, or as near thereto as permitted by a stop, 25, which is preferably provided upon the tablet, the finger standing at one side of the stop at the highest position and at the opposite side of 120

the stop at the lowest position. If it is desired to have the valve closed when the temperature reaches the highest degree indicated on the scale, the valve stem will be left 5 at said farthest withdrawn position,—that is, with the pointer standing at the highest point on the scale. This will require the maximum expansion of the chambers, 8^a, to close the valve, and they are calculated to 10 expand sufficiently to thus close it by the time the temperature has risen to the degree at which the pointer stands on the scale. If it is desired to have the valve closed at 15 a lower temperature, the stem will be rotated back to such lower temperature, in which rotation the valve will be proportionately closed so as to require less expansion to completely close it. Thus, if the valve stem is rotated to carry the pointer back to 120 20 degrees, the valve will be nearly closed at normal temperature, and expansion of the member, 8, resulting from the slight rise from normal temperature to 120 degrees F. will complete the closing of the valve.

25 I claim:

1. In combination with a casing having inlet and outlet openings, a valve for closing the inlet opening positioned and mounted for movement in the closing direction 30 past the closing position; means for operating the valve comprising an exteriorly accessible member and an expansible chamber filled with an expansible fluid located within the casing and constituting part of the 35 connection from the exteriorly accessible member to the valve.

2. In combination with a casing having inlet and outlet openings, a valve for closing the inlet opening proportioned and 40 mounted for movement in the closing direction past the closing position; means for operating said valve comprising a threaded valve stem and an interiorly threaded member with which the valve stem engages the 45 pitch of the thread being substantially equal to the full stroke of the valve from fully open to fully closed position, and an expansible chamber filled with expansible liquid situated within the casing and constituting 50 part of the connection therein from the stem beyond said thread to the valve.

3. In combination with a casing having inlet and outlet openings, a valve for closing one of said openings positioned and mounted 55 for movement in the closing direction past the closing position; means for operating the valve, comprising a two-part stem whose parts are adapted to move longitudinally with respect to each other and to engage 60 each other for rotation; exteriorly-accessible means for rotating one of said parts; an expansible chamber filled with an expansible liquid connecting the other of said parts within the casing with said valve, said 65 last mentioned member of the stem having

a threaded engagement with the casing for moving it into and out of closed position by rotation of said member, and means for checking the rotation of the exteriorly-accessible member to cause it to remain at any 70 position to which it may be manually adjusted.

4. In combination with a casing having inlet and outlet openings, a valve for closing one of said openings positioned and mounted 75 for movement in the closing direction past the closing position; a stem for said valve comprising two members, one of which extends outside of the casing for operation, the other member having threaded engagement with the casing and an expansible chamber filled with an expansible fluid connecting said last mentioned stem member with the valve, the two stem members being connected with each other for the rotation 80 of either by the other and for relative longitudinal movement; means for stopping the exteriorly-protruding stem member against longitudinal movement with respect to the casing; a graduated scale and pointer for 85 indicating the rotative movement of the exteriorly-protruding stem member, the scale being graduated in degrees of temperature.

5. In combination with a casing having inlet and outlet openings; a valve for closing one of said openings; means for operating the valve comprising a two-part stem whose two members are connected for rotation together and for relative longitudinal movement, one of said stem members protruding from the casing for exterior operation; an expansible chamber filled with expansible fluid connecting the other member of the stem with the valve, said last-mentioned stem member having threaded engagement with the casing for giving longitudinal movement to the valve by said stem member, the exteriorly-protruding stem member having a tapering shoulder facing outward and an abrupt shoulder facing inward, the casing having a shoulder facing outward, opposed to said last mentioned shoulder of the stem, and a coiled spring interposed between said shoulders for forcing the stem member outward; a washer 100 on the outer member of the stem outside said tapering shoulder and adapted to seat thereon; the casing having an outwardly-facing shoulder for seating the washer, and a bushing for clamping said washer on such seat. 110

6. In combination with a casing having inlet and outlet openings, a valve for closing one of said openings; means for operating the valve, comprising a two-part stem whose members are parted at a longitudinal dia- 125 metric plane at which they lap for longitudinal sliding upon each other; said lapping faces having each a longitudinal groove, said grooves facing each other and forming a seat for a guide pintle, each member being 130

bored axially beyond said lapping portions to continue such pintle seat, and a pintle lodged in the seat and extending fixedly into the axial bore of one of said members, and 5 adapted to be thrust into the axial bore of the other when said members are fully lapped; an expansible chamber filled with expansible fluid connecting the inner of said members with the valve, the other member 10 protruding from the case and exteriorly pro-

vided with means for rotating it and means for longitudinally stopping said exterior stem member with respect to the casing.

In testimony whereof, I have hereunto set my hand at Chicago, Illinois, this 6th day 15 of June, 1914.

GEORGE L. BOTTUM.
